KARL ARNSTEIN, OF FRIEDRICHSHAFEN, GERMANY, ASSIGNOR TO LUFTSCHIFFBAU ZEPPELIN GESELLSCHAFT MIT BESCHRANKTER HAFTUNG, OF FRIEDRICHSHAFEN, GERMANY.

HULL CONSTRUCTION OF RIGID AIRSHIPS.

Application filed September 13, 1924, Serial No. 737,595, and in Germany October 4, 1923.

My invention relates to the hulls of rigid airships, which are made up of longitudinal and cross members which constitute trusses in themselves and are diagonally braced by 5 wires. I aim to improve the construction of such hulls, especially with regard to the outer shape of the ship.

According to my invention I provide longitudinal wires intermediate the longitudinal girders and parallel to them. They serve for steadyng the outer cover which may be fastened not only to the longitudinal girders, but also to such longitudinal wires. Such wires may be supported by spacing 10 members holding them in position with relation to the points of intersection of the diagonal bracing wires of the hull. In addition supports for the longitudinal wires 15 may be provided by putting stirrups on the ring girders over which such wires lead, and at those cross members where different pieces of the outer cover abut, it is useful to provide a circumferential wire which connects the stirrups, situated on this ring, to each 20 other, thereby creating a good support for the seam in the outer cover.

The drawing represents an example embodying my invention.

Fig. 1 shows a perspective view of the 25 way of fastening and supporting the outer cover, looked at from the outside of the ship. Here part of the cover is broken away.

Fig. 2 is a corresponding view, but seen from a point inside of the ship.

Fig. 3 gives a plan view on an individual 30 piece of the outer cover, seen from within.

Fig. 4 is a cross section taken on line A—A of Fig. 3.

Fig. 5 is a cross section taken on line 35 B—B of Fig. 3, but on a larger scale.

In Fig. 1 a piece of fabric 1 is laced to a longitudinal girder 2. This piece of fabric is further supported by a longitudinal wire 3. On the ring girder 4 stirrups 40 such as shown at 5 are provided. These stirrups have a height equal to the distance between the outer chords of the longitudinal girders and of the ring girders. Over these stirrups 5 the longitudinal wires 3 lead.

At the rings where different pieces of the

outer cover meet, a circumferential wire 6 is arranged leading over the stirrups 5 and to this the cover pieces may be laced by laces 7. (See Fig. 2.)

For the purpose of tightening the wires 55 3 they are attached to the usual diagonal bracing wires 8 by means of spacing member 9.

The longitudinal wires 3 are connected with the cover by means of a ribbon 10 sewn 60 to the fabric, which has laces 11 at regular intervals.

It is understood that I do not want to limit myself to the details described or shown in the drawing as many variations 65 will be possible without diverting from the spirit of my invention.

What I claim is:

1. A rigid airship comprising a hull made up of longitudinal and cross members connected by diagonal bracing, longitudinal wires intermediate said longitudinal girders and an outer cover to said hull fastened to said longitudinal members and steadied by 70 said longitudinal wires.

2. A rigid airship comprising a hull made up of longitudinal and cross members connected by diagonal bracing, longitudinal wires intermediate said longitudinal girders and an outer cover to said hull fastened to 75 said longitudinal members and to said longitudinal wires.

3. A rigid airship comprising a hull made up of longitudinal and cross members connected by a diagonal bracing, longitudinal 80 wires intermediate said longitudinal girders, said wires being stayed by spacing members to said diagonal hull bracing, and an outer cover for said hull fastened to said longitudinal members and to said longitudinal 85 wires.

4. A rigid airship comprising a hull made up of longitudinal and cross members connected by a diagonal bracing, longitudinal 90 wires intermediate said longitudinal girders, said wires being stayed to said cross members by means of stirrups over which said wires lead, and an outer cover for said hull fastened to said longitudinal members and 95 to said longitudinal wires.

5. A rigid airship comprising a hull made up of longitudinal and cross members connected by diagonal bracing, longitudinal wires intermediate said longitudinal girders, said wires being stayed to said cross members by means of stirrups over which said wires lead, a circumferential wire in the plane of one of said cross members leading over said stirrups, and an outer cover for said hull fastened to said longitudinal members, to said longitudinal wires, and to said circumferential wire. ¹⁰

KARL ARNSTEIN.
